[57] **CLAIM**

The ornamental design for a enclosure for electrical components or the like, as shown and described.

DESCRIPTION

FIG. 1 is a perspective view of my novel ornamental design of a enclosure for electrical components or the like, with lid removed;

FIG. 2 is a top plan view thereof;

FIG. 3 is an end view thereof;

FIG. 4 is another end view thereof;

FIG. 5 is a side elevation view thereof;

FIG. 6 is another side elevation view thereof; and

FIG. 7 is a bottom plan view thereof.

The cross hatching is shown to indicate contrasting stripes.

FIG. 1

FIG. 7

FIG. 3

FIG. 5

FIG. 2
